CONTROLLING DEVICE FOR THE DRAINAGE
OF THE STEAM CYLINDER IN AN AUXILIARY
PLANT OF A LOCOMOTIVE

Ladislav Hladik, Pilsen, Czechoslovakia, assignor to Limited Company formerly Skoda Works, Plzen, Prague, Czechoslovakia, a corporation of Czechoslovakia

Application February 23, 1933, Serial No. 658,043
In Czechoslovakia March 23, 1932

2 Claims. (Cl. 277—4)

The present invention relates to apparatus for the reliable control of the drainage device for the auxiliary plant of locomotives which, as shown by experience, is one of the essential conditions for the working of the auxiliary plant, particularly in regions of difficult climatic conditions.

Hitherto either hand or automatic control of the drainage device for the auxiliary plant has been used, which was put into action for a certain length of time. It was found, however, that these methods were either unreliable and caused damage to the steam plant in the case of hand control, or in the case of automatic control they were much too complicated and difficult to adjust to the varying weather conditions.

The present invention solves the problem of the drainage device in a manner which excludes the possibility of the engineer forgetting to open the drain cock before starting up the auxiliary plant and which, at the same time, makes it possible for him to leave the drain cock open for any desired length of time after starting up the plant, according to the climate and time of year. This method of controlling the drainage device can be applied both to the ordinary mechanical opening and closing of the drainage device, and to the case which most frequently occurs, where compressed air, steam pressure, or some other compressed medium is used for operating and controlling the drainage device.

The essence of the present invention consists in apparatus assuring the drainage device always being automatically opened either at the same time, or before, the auxiliary plant is shut down, while, when the auxiliary plant is running this device still remains open until the engineer, after a suitable interval, closes it separately by hand.

The principle of this invention can be seen from the example of its application shown in the accompanying drawing. In this example compressed air or other fluid medium is used for controlling the auxiliary plant, and also for controlling the drainage device. In this connection the manner of starting and stopping the auxiliary plant can be whatever is desired, as can be the system of draining organs, and their position on the auxiliary plant or piping. The drainage organs could be, for example, valves or cocks which are arranged on the steam cylinders and which are so controlled, in a known manner, by the piston of the auxiliary air cylinder, that after the inflow of compressed air under the piston the drainage organs close, while, after the compressed air has been released from the cylinder,

a spring arranged in the appropriate place opens these organs.

In the accompanying drawing the primary three-way cock 1 is shown as the control organ which controls the shutting down and starting up of the auxiliary plant, and the secondary three-way cock 2 as the regulating organ which actuates the opening and closing of the drainage device. Figures 1, 2 and 3 show diagrams of the corresponding positions of both three-way cocks at different phases of starting up the auxiliary machine the drainage device being shown at the left of Figure 1, and Figures 4 and 5 are views of the corresponding arrangements of levers which connect these cocks.

The compressed air is supplied to the cocks 1 and 2 through the pipe 3. The pipe 4 leads from the cock 1 to the starting device of the auxiliary machine and, as soon as the compressed air reaches this pipe, the auxiliary machine is put into operation, that is, started up; when the compressed air flows out of the pipe the auxiliary machine is shut down. The manner in which this is done is not the subject of this invention, and it is therefore not necessary to go any further into this. The pipe 5 leads to the previously mentioned air cylinder of the drainage device. The channels 6 and 7 act as exhausts, for example, into the atmosphere.

The cock 1 is actuated through the lever 8 by means of the connected link rod 10 and the hand lever 9. This lever 9 is provided with a handle and the other limb 11 is connected by a link to the spring 12, which is so placed relative to the pivot of the lever 9 that it secures both limiting positions of this lever. The cock 2 is actuated by the lever 13 which is provided with a handle and carries a pin 14 which can engage in the stop 15 which is arranged at one side of the lever 10.

The operation of the device indicated in this example is as follows: With the auxiliary machine shut down the respective positions of the cocks are as shown in Figure 1, and the position of the levers is shown in Figure 4. The pipe 4 is connected to atmosphere 7, so that the auxiliary machine is shut down; the pipe 5 is also connected with the exhaust 6 and the drainage device thus opened as shown in the left hand part of Figure 1. At the same time the lever 9 assumes the position of Figure 4 and is secured in this position by the spring 12, while the one-sided stop 15 of the rod 10 holds the pin 14 of the lever 13 in the position indicated.

When starting up the auxiliary machine it is

necessary to turn the lever 9 towards the left into the position shown in Figure 5, whereby simultaneously the lever 8 of the cock 1 is also turned towards the left, while the lever 13 of the cock 2 remains in its original position; it is merely no longer secured by the stop 15. The position of the cocks is now as shown in Figure 2. The compressed air from the pipe 3 passes through the cock 1 into the pipe 4, whose connection with the exhaust 7 is interrupted and the auxiliary machine is started up. As the lever 13 has remained in its original position, the cock 2 does not alter its position, and the pipe 5 remains connected to the exhaust 6 so that the drainage device is still open.

After a certain time, depending on the season and the weather, when the engineer has made certain that all the water has passed off from the auxiliary plant and the pipe, he turns the lever 13 by hand into the position 13' (Figure 5) whereby the cock 2 is also turned into the position indicated in Figure 3. The compressed air from the pipe 3 flows into the pipe 5, whose connection with the exhaust is interrupted, and closes the drainage organ.

At any time while the auxiliary machine is working, it is possible, by turning the handle 13, to open the drainage device and to close it again.

The auxiliary machine is thrown out of service by turning the lever 9 from its position in Figure 5 into the position shown in Figure 4, whereby the one-sided stop 15 of the rod 10 strikes against the pin 14 of the lever 13 and, as a result, not only the cock 1, but also the cock 2, is turned into its opened position so that the air flows out from the tubes 4 and 5 to the exhausts 7 and 6, and the auxiliary machine is shut down while the drainage device opens. Thus, with this method, when the auxiliary steam plant is shut down, the drainage device is always simultaneously and automatically opened, thereby excluding the possibility of the engineer forgetting to do this.

It is advantageous to make the spring 17, which controls the opening of the drainage device, so strong that the drainage device opens somewhat earlier than the shutting down of the auxiliary steam plant. The oil which collects at the drainage organ while the plant is running is, by this method, properly blown out by means of steam

under full pressure, so that the drainage organs remain clean and do not get choked up.

It is also advantageous to have the throw of the pin 14 sufficiently smaller than the throw of the stop 15 that it is possible to open the cock 2 by the movement of the lever 9, but, on the other hand, it is not possible when moving the lever 13 back, to carry the spring 1 over the dead centre that is, it is not possible to start up the auxiliary plant. In this way the lever 13 and the cock 2 are secured in their opened position during the whole time that the auxiliary plant is shut down.

What I claim and desire to secure by Letters Patent of the United States is:—

1. In an apparatus for the purposes specified, two three-way cocks, an operating lever mounted on the first cock, a first hand operated lever having two end positions, a rod interconnecting said levers, a second hand operated lever mounted on the second cock, a lug projecting from the second hand lever, a projection on said rod engaging said lug only in certain relative positions of said lug and projection but free to move with respect thereto, whereby upon the movement of the first hand lever into one position the first cock is operated but the second cock is not operated by said rod, and upon the movement of the first hand lever into the second position the projection on the rod will engage the lug on the second hand lever and rotate through it the second cock from the position into which it may have been moved by the second hand lever into its normal position, the leverage on the elements being such that the first hand lever cannot be moved into the first end position by the actuation of the second hand lever.

2. The apparatus according to claim 1 and in which the first hand lever is pivoted and is provided with an arm, a spring fastened to said arm to maintain the first hand lever in either end position, whereby when the second hand lever is rotated to displace the first hand lever towards the first end position the first hand lever does not move past dead center and is returned by said spring into its second position when the pressure on the second hand lever is relieved.
